UNITED STATES PATENT OFFICE

2,536,593

KEYHOLE ILLUMINATOR

Edward E. Ciha, Chicago, Ill.

Application December 5, 1945, Serial No. 632,926

2 Claims. (Cl. 240—2.13)

1

This invention relates to a keyhole illuminator and among its objects are to provide a simple, comparatively inexpensive and practical lamp which may be secured on a door or door jamb in position to illuminate the keyhole whenever illumination is required.

Another object is to provide a lamp casing in which a small electrical dry cell is housed and connected to an electric lamp in a novel manner.

Another object is to guard against the entrance of rain or snow into the casing of the lamp and thereby avoid short circuiting of the electric circuit.

Another object is the provision of simple means for holding the dry cell in place in the casing.

Other objects and advantages will appear in the course of this specification and with all of said objects and advantages in view, this invention consists in the several novel features of construction, arrangement and combination of parts hereinafter fully set forth and more particularly defined in the appended claims.

The invention is clearly illustrated in the drawing accompanying this specification, in which:

Fig. 1 is a side elevation upon a reduced scale of a keyhole illuminator embodying a simple form of the invention applied to a fragment of a door;

Fig. 2 is a rear elevation of the keyhole illuminator with certain portions of the casing broken out;

Fig. 3 is a vertical cross section taken on the line 3—3 of Fig. 1; and

Fig. 4 is a horizontal section taken on the line 4—4 of Fig. 1.

Referring to said drawing, which is merely illustrative of the form of the present invention, 10 designates the casing of the lamp, which is preferably rectangular, closed at its front, top, bottom and sides and open at its back. Apertured lugs 11 project from the top and bottom walls of the casing to receive screws or nails, whereby to fasten the lamp upon a door or door jamb.

Secured in the cavity of the casing is a small electric dry cell 12, which serves to energize an electric lamp 13, having its bulb disposed in and behind a light opening 14 formed in one of the side walls of the casing.

An electrical connection for the electric lamp is made with one pole of the dry cell by a lamp socket 15 and a cap 16 to which the lamp socket is soldered or otherwise secured. The cap has a skirt 17 which extends from its end 18 and said

2

skirt is formed with several slits 19 to provide sections 20 between the slits which are capable of flexing slightly. The cap is formed of flexible metal and its internal diameter is substantially the same as that of the dry cell with the paper shell partially removed so as to enable the cap to be slipped upon and make contact with the zinc shell of the dry cell. In assembling the cap with the dry cell, the paper shell is removed from the dry cell at one end and the cap is slipped upon the exposed zinc shell of the dry cell.

The other pole 21 of the dry cell contacts with a metal strip 22 which is secured to one side wall of the casing as by a screw 23 and nut 24. One end 25 of the strip 22 is bent at right angles to the main body thereof and contacts with the pole 21 of the dry cell. The screw 23 may be of sufficient length to bear against the dry cell and thereby hold it in place, but I prefer to employ a metal clip 26 held in place by the screw and nut and having a curved part extending part way around the dry cell and serving to hold it in place. If desired, the casing may be formed with a saddle 27 against which the dry cell is held by the clip 26.

The metal strip 22 extends along one side wall of the casing from the bent end 25 practically to the opposite end of the casing and it is adapted to be moved into contact with the center contact 27 on the electric lamp to close the circuit thereof.

Between the metal strip 22 and adjacent the side wall of the casing is the head 28 of a push button 29 which protrudes through a hole in the side wall. The push button is luminous and has a reduced part 30 upon the end of which is applied a luminous paint 31 whereby the button may be seen in the dark, and over said reduced end is held a transparent cap 32 formed of transparent plastic or other like material. The cap 32 covers the luminous paint and protects persons from touching the paint when pressing the push button.

The metal strip 22 is formed of resilient material and yieldably holds the free end of the strip out of contact with the center contact of the electric lamp and at the same time it holds the push button in its outward position.

The open back of the casing is closed by a piece of waterproof sheet material 33, the edges of which are received in rabbeted edges of the side and bottom walls of the casing. At the top of the casing in the inner face of the top wall adjacent its edge is a groove 34 in which the

upper edge of the sheet 33 is held. With the upper edge of the sheet held in the groove, rain or snow cannot enter the casing at its top.

To prevent rain or snow from entering the casing through the holes in which the electric lamp and push button are located, a rubber gasket 35 is placed around the lamp bulb and it may be cemented to the inner face of the side wall of the casing. A rubber gasket 36 is placed between the head of the push button and the face of the adjacent side wall and, if desired, this gasket also may be cemented to the side wall. The lamp bulb and gasket and the push button and gasket seal the holes in which are contained.

Desirably the casing may be formed of Bakelite or other plastic material and it is molded in one piece. The parts of the lamp are few and are easily assembled.

The keyhole illuminator is fastened to the door 36 or door jamb adjacent the keyhole and positioned so that the light rays issuing from the lamp will be projected upon the keyhole.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a weather-proof keyhole illuminator, the combination of an elongated casing having front, side, and end walls, an electric dry cell positioned in said casing, a metallic lamp supporting member positioned between the adjacent ends of said dry cell and casing, said member having a threaded bore therein open at both ends, of a size to receive the threaded stem of an electric lamp 40 with the glass bulb thereof extending outwardly at one end of said bore and the center contact of said lamp extending outwardly at the other end of said bore, said member having a cylindrical recess therein, the axis of which extends substantially at right angles to the axis of said threaded bore, said recess being of a size to receive and frictionally engage the metallic dry cell shell adjacent the closed end thereof, a resilient, L-shaped, electrical conductor positioned 45 in and secured intermediate its ends to said casing, one end of said conductor being bent transversely to the remainder thereof and contacting the center contact of the dry cell adjacent the opposite end of said casing, the opposite free end of said conductor being positioned adjacent to but normally spaced from the center contact of said lamp, and a push button extending through a side wall of said casing adjacent said conductor, said push button operative upon inward movement thereof to move the free end of said conductor into contact with the center contact of said lamp, means carried by said casing for retaining said dry cell therein, and sealing means

for each of said electric lamp, push button, and rear wall of the casing whereby a weather-proof keyhole illuminator is formed.

2. The combination in a keyhole illuminator having an elongated casing adapted to receive an electric dry cell having a center contact, and a metallic lamp supporting member adapted to receive an electric lamp having a center contact, said lamp supporting member adapted to be mounted on and electrically connected to said dry cell, of a resilient, L-shaped conductor positioned in and secured intermediate its ends to said casing, one end of said conductor being bent transversely to the remainder thereof and contacting the center contact of the dry cell adjacent the opposite end of said casing, the opposite end of said conductor being positioned adjacent to but normally spaced from the center contact of said lamp, a push button extending through a side wall of said casing adjacent said conductor for actuating the aforesaid opposite end of the conductor to engage the contact of said lamp, a metallic clip complementally formed to the dry cell and affixed to said conductor at the point of securing said conductor to the casing, and a saddle affixed to the casing for mounting the dry cell, whereby the dry cell and the L-shaped conductor are adapted to be supported within the casing.

EDWARD E. CIHA.
